CASE AND LINK RECEIVER FOR AERIAL
MACHINE GUNS

John F. Haberlin, Seattle, Wash., assignor to
Boeing Aircraft Company, Seattle, Wash., a
corporation of Washington

Application October 6, 1936, Serial No. 104,193

6 Claims. (CL 89—37.5)

My invention relates to devices for the collection and disposal of cases and links as ejected from a machine gun, particularly one which is flexibly mounted and wholly enclosed, and, in conjunction with such a device, it relates also to a device for supplying ammunition in belts to such guns.

In airplanes the ammunition is normally supplied to the machine guns in belts of cartridges connected by links, and as each cartridge is discharged the case and a link are ejected, usually through different openings in the gun. In a case where the machine gun is fixedly mounted it is a comparatively simple matter to provide a chute whereby the ejected links and cases may be conducted overboard. With a flexibly mounted gun, however, this cannot readily be done. The chute would have to be flexibly connected to the gun in order to carry the links and cases overboard, and this would unduly restrict the freedom of action of the gun. However, the cases and links cannot be permitted to drop to the floor, for there they constitute a source of inconvenience, if not danger, to the gunner, who may step upon them and be caused to fall, or have his aim disturbed, and especially is this true in gun mounts of the type embodying an enclosure for the gun through which only its muzzle protrudes, and with which the gunner is given a wide spherical sector of fire, and where in action a considerable amount of ammunition may be fired from a given machine gun.

In such situations as the latter it has heretofore been customary to provide a chute mounted to move with the gun, terminating immediately beneath the gun in a removable sack, in which sack was received the ejected links and cases. However, such a sack could not be made sufficiently large to take a considerable number of such cases and links, for thus it would impede the freedom of movement of the gun, and furthermore its weight, when filled with any considerable number of such discharged links and cases, would become a considerable item. It was therefore made comparatively small, and when filled it had to be emptied to avoid backing up of the links and cases and possibly jamming the gun. This was sometimes accomplished by the use of slide fasteners constituting a separable metal seam, of the type commonly termed a zipper, which when opened up permitted the emptying of the sack, but whether its emptying was accomplished in this manner or by removing it from the end of the chute, there still remained the problem of disposing of the links and cases which it contained. They could

be and usually were dumped from the sack into a larger container, but then again this larger container had to be disposed of in some manner. They could not be dumped therefrom upon the floor, for if this were to occur they might as well have been permitted to drop upon the floor in the first instance, and the same reasons for avoiding this made it necessary to provide a larger container to receive them when the sack was filled. The larger container had to be carefully disposed or it would upset, spilling the links and cases upon the floor, and it could not well be dumped overboard for the reason that in modern airplanes the gunner's compartment is completely enclosed in a turret-like shell, without any aperture convenient for the disposal of such material from a container.

Thus not only was the removal and disposal of the ejected cases and links a matter of difficulty, but it also consumed considerable time, which in action could not be spared, especially as the gunner was further required to remove his ammunition box, when empty or substantially so, and to replace it with a loaded ammunition box, and to feed his belt into the machine gun.

According to the present invention these difficulties are largely obviated by a construction in which, at the time of removing the empty ammunition box, there is removed, without further thought or effort on the part of the gunner, the ejected cases and links, and these are properly stowed away, without danger of their spilling upon the floor, merely by the placing of the empty ammunition box in its place upon the ammunition supply rack from which it was originally taken, and when the new ammunition box is placed in operative relationship to the gun there is at the same time, and without thought or effort on the part of the gunner, a receiver placed in proper relationship to the gun to receive the cases and links from the gun as the new belt of ammunition is used.

My invention, therefore, comprises the novel ammunition box and associated parts, and the novel mounting and combination thereof with the gun, the gun mount, and the enclosing shell as part of the aircraft structure, all as shown in the accompanying drawings and as will be more fully described and claimed in this specification.

In the accompanying drawings I have shown my invention in a typical form, and in association with a typical aircraft structure, machine gun, and mount, it being understood that the individual elements may be varied, as will be made clear hereafter.

It should be borne in mind further that while the invention is particularly designed for use upon airplanes, to meet a practical and real problem which has arisen in that field, its principles are also applicable to other types of gun mounts, as for example upon armored cars or tanks.

Figure 1 is a sectional view of a typical gun and mount, parts being broken away, and showing my invention associated therewith.

10 Figure 2 is an elevation from the rear or breech end of the gun, showing the same arrangement, though showing only the immediately supporting part of the aircraft structure.

15 Figure 3 is a perspective view of the ammunition box, the case and link container, and the chute, in operative relationship to each other.

18 Figure 4 is a rear elevation of a slightly modified form of the case and link receiver.

20 The installation illustrated shows a machine gun 9 supported upon a shell or sphere 8, which is flexibly mounted upon the fuselage 7 of an aircraft in such a way as to give the gun a wide degree of flexibility and a substantially hemispherical field of fire. To accomplish this a nose 25 turret 10 may be mounted to rotate about a longitudinal axis A, being supported from a track 11 by means such as the rollers 12. This turret 10 has an aperture 13 receiving the spherical shell 8, which shell is pivotally mounted, by means 30 not shown, to pivot about a transverse axis B with relation to the turret 1, for elevational movement of the gun. The shell 8 includes framework 80, wherein is pivoted a ring 81 upon an axis represented by the trunnions 82 and 35 indicated at C in Figure 2, and about the axis of the ring 81 is rotative a ring 83, supported by the rollers 84. The ring 83 has secured to it a forwardly and somewhat downwardly inclined bow 85, from the central portion of which, 40 between its ends, extends rearwardly a gun mount 86, suitably braced from the ring 83, upon which the gun is mounted in its intended or usual manner. It will thus be seen that the gun may be traversed by movement about the axis C, that 45 it may be elevated and depressed by movement about the axis B, and that it may be positioned in any desired position about the axis A, and by rotation of the ring 83 relative to the ring 81 the gun may always be maintained upright, 50 regardless of its rotation around the axis A. It will be observed, too, that this construction leaves the shell 8 at one side of the gun and gun mount entirely free of structural members. There is 55 no difficulty in inserting or withdrawing a large container from the breech end of and alongside the gun.

Such a container comprises a box generally designated by the numeral 1, and having a partition between its top and bottom designated by 60 the numeral 10. This divides the box into an upper chamber 11, of a shape and size, at least when filled, to contain a belt of live, link-connected cartridges, and a lower chamber 12 of a size (at least when the chamber 11 is empty) to receive readily the same number of ejected links and cases as will comprise the belt within the chamber 11. The upper chamber 11 is provided with a feed opening at 13, through which the 65 belt of ammunition is fed, and the lower chamber 12 is provided with an opening 14, preferably located well above its bottom, for the receipt of the ejected cases and links. Because of space limitations within the shell 8 the lower chamber 70 75 of the box may be elongated, so that it may

have sufficient capacity without increasing its depth.

The gun, adjacent its feed opening, is provided with a support 91, with which a complementary support 19 on the box 1 is engageable quickly and easily, and as easily disengageable. Preferably the member 19 is of inverted U shape, and the member 91 is merely a longitudinally extending bar, so that by movement of the box 1 lengthwise of the gun from its breech end toward 10 its muzzle end, and then by slight downward movement of the box, the box may be supported on the support 91, and be thereby fixed in operative position with relation to the gun's feed opening. The support 91 is in effect mounted upon the gun mount, although usually carried upon the gun itself, and it is largely immaterial in what manner it is supported so long as it adequately supports the ammunition box and locates the latter properly with relation to the 20 gun and to the chute, and, of course, the support must be of such character that it can be readily engaged and disengaged, and preferably by the simple type of longitudinal and vertical motion described above. As a means of further 25 supporting the box 1, and particularly against side sway, it is engaged at opposite sides by rollers 87 or other guide means supported from the shell 8, or more specifically from the ring 83.

The gun discharges links from a link-ejection 30 opening on the side opposite its feed opening, and ejects cases from a case-ejection opening in its bottom. Appropriate chutes are therefore provided, as the chute 2 and the chute 20, the first to receive the ejected cases and the second 35 to receive the ejected links. Both these chutes may join, and terminate at a point which, when the several elements are properly supported relative to each other, will discharge the cases and links into the opening 14 of the lower chamber 40 12 of the box. The chutes are supported in any suitable manner, though they should be independent of the box 1. The support for them, as herein shown (see Figure 2), consists of a bracket 21 permanently fastened upon the gun 45 mount 86 and to which the chute is semipermanently secured, as by screws or bolts (not shown).

With the construction described it will be apparent that the chutes 2 and 20 are located permanently in position with respect to the gun, and with respect to the position which will be assumed by every ammunition box when it is supported upon the support 91. The gun is secured in position upon its mount 86 with its muzzle only protruding from the shell 8 through a slot 88 therein (Figure 55 1). An ammunition box may be removed from a rack (not shown) within the fuselage 7, where it may be supported by a support analogous to the member 91, moved into the shell 8 alongside the gun, and the shell, it will be noted, is entirely unobstructed in the operative position to be assumed by the box and to the rear thereof. Thus the box may be pushed in without difficulty, engaged with the support 91, and when thus supported will be fixed in operative relationship to the gun and to 60 the chutes 2 and 20. The belt of ammunition is fed to the gun, and as it is discharged and the cases and links are ejected they fall by gravity through the respective chutes (the gun being always maintained substantially upright by means 65 of the flexible connections described), and these ejected cases and links are received in the chamber 12. The capacity of the latter, it will be remembered, is sufficient to contain all the cases and links comprising the belt of ammunition and 70 75

originally contained in the chamber 11. It may be of larger or of variable capacity, if desired. When the belt of ammunition is exhausted, all the cases and links will be found in the lower chamber, and the box is removed by raising it slightly to disengage the support 19 from the support 91, is then moved rearwardly toward the breech end of the gun, and is replaced upon its rack. A new box filled with live ammunition is immediately taken from the rack and placed upon the support 91, the belt of ammunition is fed to the gun, and the gun is immediately ready to reopen fire. The entire operation takes but a few seconds. The ammunition is kept in the chamber 12 until it is convenient to remove it, and the gun is out of action but a short time, and only such time as would be required in any event to remove an empty ammunition box and to supply a full one.

To assist in preventing spilling of the cases and links from the chamber 12 I may provide a flap or door 16, as shown in Figure 4, pivoted at 16 and urged by a spring 17 into a position to close the opening 18. When the box is being mounted upon the gun the closure 15 may be held down against the spring 17, and when it is removed the spring 17 will immediately throw the closure upward into closed position, where it will prevent accidental spilling out of the cases and links. It is held in the open position when the box is in operative relationship to a gun by engagement with a roller 27, or by engagement with the chute 2.

I do not claim as my invention the ammunition box in the form of the upper chamber 11, which is not my invention, but the essence of my invention lies in the combination with such an ammunition box of a chamber for the reception of ejected cases and links, and of a capacity to hold those cases and links which originally comprised the belt of live ammunition in the box above, the whole being so connected and supportable as to be placed in operative relationship to the gun and chutes by a simple type of movement.

What I claim as my invention is:

1. In combination with a machine gun for use upon an airplane or the like, and an enclosing and supporting shell for the gun, through which only its muzzle protrudes, flexibly mounted upon the airplane, an ammunition box for the supply of ammunition to the gun in link-connected belts, said box being partitioned to define an upper and a lower chamber each having an opening, the upper chamber being shaped to contain such a belt of ammunition and to feed the same through its opening direct to the gun, the lower chamber being of appropriate size to contain the same number of ejected links and cases, received through its opening, complemental means carried the one by the box and the other upon the shell, quickly interengageable and disengageable to support said box in operative relationship to the gun, and means independent of said box and carried upon the shell in operative relationship to the gun and to the lower opening of the box, to conduct to and discharge through the latter, into the lower chamber, the links and cases as ejected from the gun.

2. In combination with a machine gun for use upon an airplane or the like, and an enclosing and supporting shell for the gun, through which only its muzzle protrudes, flexibly mounted upon the airplane, a box for the supply of ammunition to the gun in link-connected belts, said box being partitioned to define an upper chamber having an opening and shaped to contain such a belt and to feed it, through its opening, direct to the gun, and to define a lower chamber of a size to

receive and contain all such links and cases when ejected from the gun, and having an opening to admit the same, complemental means carried the one by the gun and other by the box, quickly interengageable by movement of the box lengthwise of the gun and then downwardly relative to the gun, to support the box in operative relationship to the gun, and disengageable by reverse movement, the shell being unobstructed in rear of the space occupied by the box in such operative position to facilitate its engagement and disengagement, and means independent of the box and carried upon the shell in operative relationship to the gun and to the lower chamber, to conduct to and discharge within the latter, through its opening, the links and cases as ejected from the gun.

3. In combination with a machine gun for use upon an airplane or the like, an enclosing shell including a revolvably mounted ring and a forwardly directed bow supported upon said ring, the shell having an aperture for the protrusion of the muzzle of the gun, a gun mount extending rearwardly from said bow, between its ends, whereon the gun is mounted, to move with the ring, a box shaped to be received within the ring, between the bow and the gun mount and gun, the shell being unobstructed within and to the rear of such space, for ready movement of the box therewith and therefrom, means readily interengageable between the box and gun to support the box from the gun and in operative relationship thereto, and readily disengageable, said box being partitioned to define a first and a second chamber each having an opening, the first chamber's opening registering with the feed opening of the gun when the box is held in operative position, to feed ammunition, in a link-connected belt, directly thereto from the first chamber, and chute means independent of the box, supported from and movable with the ring, and disposed to receive links and cases as ejected from the gun, and to conduct and deposit them, through the second opening, within the second chamber, this lower chamber being of a size to receive all the cases and links constituting the belt originally contained in the upper chamber.

4. An ammunition container for use with a flexibly mounted machine gun on an airplane or the like, comprising a box partitioned to define an upper chamber to contain a belt of ammunition, and having an appropriate opening for feeding the same to the gun, and to define a lower chamber of a size to receive all the links and cases as ejected from the gun, and originally constituting such belt, and having an opening for the reception of the links and cases, means on the box for ready engagement with complemental means to support the box in operative position relative to the gun, and a closure for the lower opening spring-urged to closed position.

5. In combination with a machine gun for use upon an airplane or the like, and a flexible mount whereon said machine gun is secured, an ammunition box support and a chute each fixed in position relative to and movable with the gun mount, and the chute having appropriate openings located to receive cases and links ejected from the gun, and to discharge the same, a box having means readily engageable with and disengageable from said support to fix the box definitely relative to the gun and relative to the discharge opening of the chute, said box being partitioned to define a chamber for a belt of live ammunition and a chamber for ejected cases and links, and

being removable from and replaceable as a unit upon said support, and having appropriate openings registering, when the box is positioned by the support, with the feeding opening of the gun and with the discharge opening of the chute.

6. In combination with a machine gun for use upon an airplane or the like, and a flexible mount whereon said machine gun is secured, an ammunition box support fixed in position relative to and movable with the gun mount, a box carrying supporting means and readily engageable as a unit with and disengageable as a unit from said

support, independently of the gun, and having appropriate openings for feeding of live ammunition and for the reception of ejected cases and links, and being partitioned to define a chamber, from which leads the feed opening, for a belt of .5 live ammunition, and a second chamber for the reception of the cases and links, the engagement of the box-carried supporting means with mount-carried supporting means fixing the box's feed opening and receiving opening in operative relation to the gun.

JOHN F. HABERLIN.
